Specification for Design.

Patented Aug. 5, 1913.

Application filed May 11, 1912. Serial No. 696,726. Term of patent 7 years.

To all whom it may concern:

Be it known that we, WILLIAM W. SLOANE and NORMAN S. RICHMOND, residing at Chicago, in the county of Cook and State of Illinois, have invented a Design for a Casing for Automobile Tire-Pumps, of which the following is a specification, reference being had to the accompanying drawing, forming part thereof.

Figure 1 is a side elevation of the casing of the pump showing our design. Fig. 2 is

an end elevation of the casing of the pump shown in Fig. 1.

We claim:

The ornamental design for a casing for an automobile tire pump as shown.

WILLIAM W. SLOANE.
